(57) **CLAIM**

(**) Term: **14 Years**

The ornamental design for a moist snuff container for use with cigarette pack, as shown and described.

(21) Appl. No.: **29/298,148**

DESCRIPTION

(22) Filed: **Nov. 29, 2007**

FIG. 1 is a front view of the design for the moist snuff container for use with cigarette pack in a closed position;

(30) **Foreign Application Priority Data**

FIG. 2 is a rear view of the design of FIG. 1;

May 31, 2007 (EM) 000734785

FIG. 3 is a right side view of FIG. 1; The left side view being a mirror image thereof;

(51) **LOC (9) Cl.** 27-06

FIG. 4 is a top view of the design of the present invention;

(52) **U.S. Cl.** D27/189; D9/432

FIG. 5 is a bottom view of the design of FIG. 1;

(58) **Field of Classification Search** D27/183-194;

FIG. 6 is a front perspective view of the design of the present invention with the cover in a partially open position and the internal slider box fully inserted;

D9/423, 430-433; 206/236-241, 242-276,

206/86, 91-95; 229/160.1

FIG. 7 is a front perspective view of the design of the present invention with the internal slider box partially withdrawn;

See application file for complete search history.

FIG. 8 is a front perspective view of the design of the present invention as used in a cigarette pack; and,

(56) **References Cited**

FIG. 9 is a front perspective view of the design of the present invention as partially withdrawn from a cigarette pack.
